UNITED STATES PATENT OFFICE.

WILLIAM A. LORENZ, OF HARTFORD, CONNECTICUT, ASSIGNOR TO THE OTAKA FABRIC COMPANY, OF HARTFORD, CONNECTICUT, A CORPORATION OF CONNECTICUT.

PAPER CRINKLING.

Application filed July 2, 1921. Serial No. 482,128.

To all whom it may concern:

Be it known that I, WILLIAM A. LORENZ, a citizen of the United States, residing in Hartford, in the county of Hartford and State of Connecticut, have invented certain new and useful Improvements in Paper Crinkling, of which the following is a specification.

This invention relates to transversely crêping or crinkling a web of paper.

The object of the invention is to crêpe the paper by a simple and inexpensive device, which may be operated at low cost, and which crêpes the paper at high speed and produces an improved character of crêping.

According to the present improvements, the crêping is effected by the co-operation of two adjacent cylinders, which may run just out of contact in either the same or opposite directions. There is provided means for carrying a web of paper over a suction cylinder, then releasing the vacuum in the cylinder, and transferring the paper to a slower-moving vacuum cylinder or drum, and causing the paper to be crinkled on that cylinder, which is provided with a strong vacuum. The first cylinder may for example be twice the diameter of the second, and may run at double the surface speed of the second. The slow or second cylinder is perforated and contains a vacuum device, the effect of which is to suck the paper against the slow cylinder as fast as it is delivered thereto by the first or rapid cylinder. The paper is delivered to the slow cylinder much more rapidly than the latter rotates, so that the effect of the suction is not only to strip the paper from the rapid cylinder, but also to crêpe or crinkle the paper transversely, in which condition it is delivered from the machine by the slow cylinder. The paper may be moistened in preparation for the crinkling, and may be held to the rapid cylinder by means of a relatively weak vacuum effective through perforations in the cylinder.

Other features and advantages will hereinafter appear.

In the accompanying drawings,

Figure 1 is a sectional plan of the apparatus, taken at about the line 1—1 of Figure 2.

Figure 2 is a sectional elevation of the

same, taken at about the line 2—2 of Figure 1.

Figure 3 is a fragmentary view on a larger scale, to illustrate diagrammatically the behavior of the paper at the point of transference from the rapid cylinder to the slow one.

Figure 4 is a diagram to illustrate the operation when the cylinders are turned in opposite directions.

Figure 5 is a diagram showing how the paper may be crushed against a doctor-blade placed between the cylinders.

The web of paper is paid off from a supply roll 10, having a weighted friction strap 11. The web passes over a guide-roll 12 and onto a large hollow cylinder 13, having numerous closely-spaced perforations 14 throughout. The web passing around this cylinder is indicated at 15, and it may be moistened by means of a sprinkler pipe 16, throwing jets 17 against the paper at the bottom of the cylinder. This moistening renders the paper softer, so as to conduce to the efficiency of the crêping device.

At the delivery side of cylinder 13 is mounted a slow crêping or crinkling hollow cylinder 18 of preferably half the diameter of cylinder 13, and provided throughout with perforations 19, which may be much more closely spaced than the perforations 14 in the main cylinder.

These two cylinders are connected to rotate simultaneously; the stub shaft 20 of the large cylinder having a gear 21 which meshes with an idle pinion 22, the latter meshing with a gear 23 of small cylinder 18, which may thus rotate in the same direction as the large cylinder, as indicated by the arrows. The cylinders in practice are placed almost in contact, being separated by a distance equal to about the thickness of the paper web. The surface speed of the small cylinder may equal about half the surface speed of the large cylinder.

As a preferred means for enabling the rapid cylinder to carry the paper around and deliver it to the slow cylinder, air is exhausted from the rapid cylinder through vacuum pipe 24 threaded into the end of a hollow hub 25 cast upon a hollow stationary core 26, upon which the revolving hollow cylinder 13 closely fits; said cylinder 13

having ends 27, 28, which fit closely to the ends of the hollow cylindrical core 26. The latter has a series of peripheral depressions 29 communicating by passages 30 with the interior of the vacuum core 26, these depressions 29 forming conduits for the air drawn in through the perforations 14 in the main cylinder 13. The series of depressions 29 extends around the stationary vacuum core only far enough to affect that portion of the cylinder 13 whose perforations are covered by the web 15; and no air enters through the perforations in the remainder of the cylinder 13, which remainder runs in contact with the imperforate cylindrical surface of the vacuum core at 32. Thus the paper may be held to the rapid cylinder or carrier by a comparatively weak suction, and delivered thereby to the crinkling cylinder 18.

Said crinkling cylinder 18 may also be provided with a stationary cylindrical exhaust core 33, having in its periphery depressions 34, communicating by passages 35 with the interior of the exhaust core, the latter having an exhaust opening 36 at one end. The cylinders are each provided with a closing end and a driving end, and otherwise the construction of cylinder 18, with the exhaust core and its appurtenances, may correspond substantially with that of cylinder 13; and the depressions 34 may form conduits whereby the air is exhausted through the perforations 19 in the crinkling cylinder. The grooves 34 in the crinkling cylinder may extend nearly to the point of closest approach of the two cylinders, and a much higher vacuum may be maintained in the small cylinder than in the large, with the result that the atmospheric pressure strips the paper from the large cylinder and crushes it against the small cylinder. Inasmuch as the surface speed of the small cylinder is much less than that of the large cylinder, it results that the paper is packed or pressed by the atmospheric pressure against the small cylinder in a manner to produce irregular plaits or wrinkles, whose characteristics depend to some extent upon the difference in speed of the two cylinders. The paper being damp and the exhaust being powerful in the small cylinder, an effective crêping of the paper is thus effected by atmospheric pressure.

The crêped or crinkled paper may be delivered by the small cylinder at 37 and carried off in any usual manner. Since half or more of the small cylinder is not wrapped with paper, the imperforate portion 38 of the exhaust core therein may extend around half or more of its periphery; and if desired the groove in the main cylinder may terminate at a point 39 well in advance of the line of nearest approach of the cylinders, so that the paper may be earlier re-

leased from the control of the vacuum in the rapid cylinder, and may thereupon be more easily stripped from the rapid cylinder.

Referring to Figure 3, it will be seen that, inasmuch as the cylinders are placed closely together, and inasmuch as the irregular plaiting or crêping tends to fill the space in the bight of the cylinders, an obstruction may be formed by the advancing web at 40, which tends to choke the space between the cylinders, and which forms an obstacle against which the main cylinder tends to crush the advancing paper, so that the latter may be crinkled partly by the crushing against the obstacle and partly by atmospheric pressure of the crushed paper against the slow cylinder.

At Figure 4 the cylinders are illustrated as revolving in opposite directions, and the paper passes through the constricted throat between the cylinders; the arrangement of the vacuum core for the small cylinder being the opposite of the arrangement at Figure 2, so that suction takes place only in perforations that are covered by the crinkled paper. The grooving in both the upper and lower vacuum cores may be disposed with a slight neutral space between the exhaust areas of the two cylinders, as in Figure 2, so that the paper is readily stripped from the large cylinder by the small cylinder. The paper is irregularly plaited against the small cylinder; and, if desired, the obstruction formed by this plaiting may constitute an obstruction against which the large cylinder tends to crush the paper, thus more effectually crinkling the same.

At Figure 5 the arrangement is the same as at Figure 2, except that the cylinders are more separated to permit the introduction of a thin doctor-blade 41 between the cylinders, against the edge of which the paper may be driven by the large cylinder 13, whereby the paper is stripped from the large cylinder and at the same time crinkled, the crinkled paper being taken away by the small vacuum cylinder, against which the crimped paper is pinched by atmospheric pressure, to complete the crinkling.

Variations may be resorted to within the scope of the invention, and portions of the improvements may be used without others.

Having thus described my invention, I claim:

1. A paper-crinkling apparatus comprising adjacent cylinders connected to run at different surface speeds, the slow being a hollow vacuum cylinder and having perforations such that the pressure of air crinkles the paper thereagainst as the paper is delivered at a relatively high speed by the fast cylinder.

2. The combination of a perforated hollow revolving vacuum cylinder, and means to deliver a web thereto at a speed in excess

of the surface speed of said cylinder, whereby the pressure of air may crinkle the paper against said cylinder.

3. The combination of a perforated hollow revolving vacuum cylinder, means to deliver a web thereto at a speed in excess of the surface speed of said cylinder, whereby the pressure of air may crinkle the paper against said cylinder, and means to deliver 70 the crinkled paper from the cylinder.

4. The combination of a perforated hollow revolving vacuum cylinder, means to deliver a web thereto at a speed in excess of the surface speed of said cylinder, whereby 15 the pressure of air may crinkle the paper against said cylinder, means to deliver the crinkled paper from the cylinder, and a hollow stationary vacuum core fitting within said cylinder, and having passages to communicate with the perforations in said cylinder.

5. The combination of a perforated hollow revolving vacuum cylinder, means to deliver a web thereto at a speed in excess of 25 the surface speed of said cylinder, whereby the pressure of air may crinkle the paper against said cylinder, means to deliver the crinkled paper from the cylinder, and a hollow stationary vacuum core fitting within 30 said cylinder, and having passages to communicate with the perforations in said cylinder, said passages extending to the point where the cylinder receives the web.

6. The combination of a perforated hollow revolving vacuum cylinder, means to deliver a web thereto at a speed in excess of the surface speed of said cylinder, whereby the pressure of air may crinkle the paper against 35 said cylinder, means to deliver the crinkled paper from the cylinder, and a hollow stationary vacuum core fitting within said cylinder, and having passages to communicate with the perforations in said cylinder, said passages extending from the point where 40 the cylinder delivers the web to the point where the cylinder receives the web.

7. A rapid suction cylinder for carrying paper to a slow suction cylinder whereby 45 the paper is stripped from the rapid cylinder and crinkled by atmospheric pressure on the slow cylinder.

8. The combination of a hollow perforated vacuum cylinder, and a cylinder adjacent thereto to run at high speed for delivering 50 paper to said vacuum cylinder, by which the paper is crinkled by atmospheric pressure.

9. The combination of a hollow perforated vacuum cylinder, and a cylinder adjacent thereto to run at high speed for delivering paper to said vacuum cylinder, by which 55 the paper is crinkled by atmospheric pressure, said rapid cylinder being a perforated, hollow vacuum cylinder.

10. The combination of a hollow perforated vacuum cylinder, a cylinder adjacent 60

thereto to run at high speed for delivering paper to said vacuum cylinder, by which the paper is crinkled by atmospheric pressure, means to produce a vacuum in the rapid cylinder from the intake side thereof to the 70 delivery point thereof, and means to produce a vacuum in the slow cylinder from the intake point thereof.

11. The combination of a hollow perforated vacuum cylinder, a cylinder adjacent 75 thereto to run at high speed for delivering paper to said vacuum cylinder, by which the paper is crinkled by atmospheric pressure, means to produce a vacuum in the rapid cylinder from the intake side thereof to the 80 delivery point thereof, and means to produce a vacuum in the slow cylinder from the intake point thereof, said cylinders rotating in the same direction.

12. The combination of a hollow perforated vacuum cylinder, a cylinder adjacent thereto to run at high speed for delivering paper to said vacuum cylinder, by which the paper is crinkled by atmospheric pressure, 85 means to produce a vacuum in the rapid cylinder from the intake side thereof to the delivery point thereof, and means to produce a vacuum in the slow cylinder from the intake point thereof, the slow cylinder being about half the diameter of the rapid 90 cylinder.

13. The combination of a hollow perforated vacuum cylinder, a cylinder adjacent thereto to run at high speed for delivering paper to said vacuum cylinder, by which the paper is crinkled by atmospheric pressure, 95 means to produce a vacuum in the rapid cylinder from the intake side thereof to the delivery point thereof, and means to produce a vacuum in the slow cylinder from the intake point thereof, the slow cylinder being about half the diameter of the rapid cylinder, and geared to revolve at about 100 half the surface speed of the latter.

14. The combination of a hollow perforated vacuum cylinder, a cylinder adjacent thereto to run at high speed for delivering paper to said vacuum cylinder, by which the paper is crinkled by atmospheric pressure, 110 means to produce a vacuum in the rapid cylinder from the intake side thereof to the delivery point thereof, and means to produce a vacuum in the slow cylinder from the intake point thereof, the slow cylinder being about half the diameter of the rapid cylinder, and geared to revolve at about 115 half the surface speed of the latter, said cylinders revolving almost in contact.

15. The combination of a hollow perforated vacuum cylinder, and a cylinder adjacent thereto to run at high speed for delivering paper to said vacuum cylinder, by which the paper is crinkled by atmospheric pressure, 120 the rapid cylinder having a stationary cylindrical exhaust core, with pas- 125

1. The process of crinkling paper, comprising carrying it around a relatively rapid cylinder by means of atmospheric pressure, and stripping it from said cylinder by means of a slowly-moving perforated cylinder having a high degree of vacuum, which crinkles the paper as it is stripped from the fast cylinder, each of said cylinders having a vacuum core provided with passages communicating with perforations in said cylinders from the intake side to the delivery point, and from the vacuum cylinder on the delivery side to a point beyond the delivery point of the rapid cylinder, well in advance of the line of nearest approach of the cylinders. 75
2. The process of crinkling paper, comprising carrying it around a relatively rapid cylinder by means of atmospheric pressure, releasing the paper from the control of atmospheric pressure on said rapid cylinder, and then stripping it from said cylinder by means of a slowly-moving perforated cylinder having a high degree of vacuum, which crinkles the paper as it is stripped from the fast cylinder. 80
3. The process of crinkling paper, comprising causing it to adhere to a rapidly-revolving cylinder, and to form an obstruction in the bight between said cylinder and a slowly-revolving cylinder turning in the same direction as the rapid cylinder, crinkling the paper against such obstruction, and causing the crinkled paper to be carried off by the slow cylinder. 85
4. The process of crinkling paper, comprising causing it to adhere to a rapidly-revolving cylinder, and to form an obstruction in the bight between said cylinder and a slowly-revolving cylinder turning in the same direction as the rapid cylinder, crinkling the paper against such obstruction, and causing the crinkled paper to be carried off by the slow cylinder. 90
5. The process of crinkling paper, comprising carrying it around a relatively rapid cylinder, and stripping it from said cylinder by means of a slowly-moving perforated cylinder having a high degree of vacuum, which crinkles the paper as it is stripped from the fast cylinder. 95
6. The process of crinkling paper, comprising carrying it around a relatively rapid cylinder by means of atmospheric pressure, and stripping it from said cylinder by means of a slowly-moving perforated cylinder having a high degree of vacuum, which crinkles the paper as it is stripped from the fast cylinder. 100
7. The process of crinkling paper, comprising carrying it around a relatively rapid cylinder by means of atmospheric pressure, and stripping it from said cylinder by means of a slowly-moving perforated cylinder having a high degree of vacuum, which crinkles the paper as it is stripped from the fast cylinder. 105
8. The process of crinkling paper, comprising carrying it around a relatively rapid cylinder by means of atmospheric pressure, and stripping it from said cylinder by means of a slowly-moving perforated cylinder having a high degree of vacuum, which crinkles the paper as it is stripped from the fast cylinder. 110
9. The process of crinkling paper, comprising carrying it around a relatively rapid cylinder by means of atmospheric pressure, and stripping it from said cylinder by means of a slowly-moving perforated cylinder having a high degree of vacuum, which crinkles the paper as it is stripped from the fast cylinder. 115
10. The process of crinkling paper, comprising carrying it around a relatively rapid cylinder by means of atmospheric pressure, and stripping it from said cylinder by means of a slowly-moving perforated cylinder having a high degree of vacuum, which crinkles the paper as it is stripped from the fast cylinder. 120
11. The process of crinkling paper, comprising carrying it around a relatively rapid cylinder by means of atmospheric pressure, and stripping it from said cylinder by means of a slowly-moving perforated cylinder having a high degree of vacuum, which crinkles the paper as it is stripped from the fast cylinder. 125
12. The process of crinkling paper, comprising carrying it around a relatively rapid cylinder by means of atmospheric pressure, and stripping it from said cylinder by means of a slowly-moving perforated cylinder having a high degree of vacuum, which crinkles the paper as it is stripped from the fast cylinder. 130

kling the paper against a doctor-blade between said cylinders, and causing the crinkled paper to be carried off by the slow cylinder.

- 5 29. In a paper crinkling apparatus and in combination, adjacent hollow vacuum cylinders against which paper is adapted to be held by pressure and from one to the other

of which the paper is transferred in such manner that it is crinkled; and means for driving the same at different speeds.
